United States Patent

Des. 235,396
Patented June 17, 1975

235,396

CHAIR

Kunio Onoguchi, Tokyo, Japan, assignor to France
Bed Co., Ltd., Tokyo, Japan

Filed Feb. 28, 1973, Ser. No. 336,501

Term of patent 3½ years

Int. Cl. D6—01

U.S. CL. D6—76

FIG. 1

FIG. 4

FIG. 2

FIG. 5

FIG. 3

FIG. 1 is a top plan view of a chair showing my design;
FIG. 2 is a front elevational view thereof;
FIG. 3 is a bottom plan view thereof;
FIG. 4 is a right side elevational view thereof;
FIG. 5 is a rear elevational view thereof; and
FIG. 6 is a perspective view thereof.
The left side elevational view is a mirror image of
FIG. 4 and is omitted.

I claim:

The ornamental design for a chair, as shown and de-
scribed.
